UNITED STATES PATENT OFFICE.

PETER GRABLER AND FRED H. KELSEY, OF CLEVELAND, OHIO, ASSIGNORS TO THE SIMPLEX SPECIALTY COMPANY, A CORPORATION OF OHIO.

VALVE.

1,204,972.

Specification of Letters Patent. Patented Nov. 14, 1916.

Application filed August 4, 1914. Serial No. 854,928.

To all whom it may concern:

Be it known that we, PETER GRABLER and FRED H. KELSEY, citizens of the United States, residing at Cleveland, in the county 5 of Cuyahoga and State of Ohio, have invented new and useful Improvements in Valves, of which the following is a specification.

This invention relates to a device to be 10 attached to an explosive engine of the type employed in driving automobiles, motor boats, and the like, for controlling or varying the air supply to the manifold of the engine.

15 One of the objects of the invention is to provide means for controlling or varying the supply of air to the manifold, and to vary the temperature of the air in accordance with the demands of the engine, where- 20 by a maximum efficiency of the engine is secured, and the engine is at the same time economically operated.

25 A further object is to provide means whereby kerosene, or the like, may be introduced into the cylinder of the engine while the latter is running, for the purpose of cleaning off carbon deposit in the cylinder.

30 A further object is to provide means convenient to the driver, for the ready control and manipulation of the device.

The invention will be hereinafter fully set forth and particularly pointed out in the claims.

35 In the accompanying drawing: Figure 1 is a view of a portion of an automobile, with our invention applied thereto, parts being shown in section. Fig. 2 is an enlarged perspective view of the control de- 40 vice detached. Fig. 3 is a longitudinal sectional view. Fig. 4 is a cross sectional view. Fig. 5 is a detail view of the valve operating member.

45 Referring to the drawing, 10 designates an automobile body, shown conventionally, 11 the engine, and 12 the manifold, of the engine, all of which may be of any usual or preferred construction. Secured to the dashboard 13 of the automobile is a valve 50 casing 14 provided with a cylindrical chamber 15 closed by end caps 16, one of which is provided with an opening 17. The caps are interchangeable and may be secured to the casing in any preferred manner. As

shown in the drawing, the ends of the cas- 55 ing are threaded internally, and the caps are correspondingly threaded, and provided with squared portions 18 to be engaged by a wrench. The casing 14 is provided with two inlet openings 19, 20, located at each 60 end, respectively, and leading to the said openings are pipes 21, 22, respectively. Leading outwardly from the chamber 15 are two outlet ports which communicate with a common outlet chamber 23 having a dis- 65 charge opening 24 which is connected by a pipe 25 with the manifold 12. Within the valve chamber 15 is a slide valve 26, prefer- 70 ably cylindrical in form and corresponding in diameter to the diameter of the chamber. Said valve is approximately a little longer 75 than half the length of the valve chamber so that when the valve is at either extreme of its movement it will close one inlet opening and one outlet port, and when in its intermediate position it will close both outlet ports, leaving the inlet openings uncovered. The operating rod for the valve extends through the opening 17, and is provided at its other end with an operating button 30. 80 The operating rod 27 is also passed through a flexible conduit 31, one end of which is secured within the opening 17, the other end being secured in the lower end of a guide sleeve 32 carried by arms 33 secured to the 85 steering column 34 in any suitable manner. The rod 27 extends through the sleeve 32 and is secured to the sleeve-like extension of the button 30. A spring catch 35 is se- 90 cured to the guide sleeve 32, said catch hav- 95 ing a lip to engage said button 30 or a groove 36 in the cylindrical portion of said button, so as to lock the valve in either ex- treme of its movement. It will be noted that the inlet pipe 22 has its inlet end 28 wrapped around the exhaust 29 of the 95 engine. The casing 14 is provided with a transverse boss 40 located opposite the dis- charge opening 24 and communicating with the outlet chamber 23. Connected with said 100 boss by a pipe 41 is a priming cup 42, con- trolled by a valve 43.

During the operation of the engine it is sometimes desirable to supply air to the manifold of the engine, in addition to that 105 which passes through the carburetor, and the efficiency of the engine at these times, depends upon whether the auxiliary air that

is admitted, is hot or cold. By moving the valve 26 so as to cover the inlet opening 20, the adjacent outlet port is also covered, whereupon the suction of the engine draws 5 cold air through pipe 21 into the chamber 15 and thence into the outlet chamber 23, and finally through the discharge port 24 to the manifold 12. Should heated air be 10 desirable, the valve is shifted to cover opening 19 and uncover opening 20, whereupon the air passing to the manifold will be drawn through the pipe 22, which air is heated by radiation from the exhaust. If 15 it is desired to prevent an auxiliary supply of air to the manifold, the valve is moved to its intermediate position to cover both outlet ports. Should it become necessary to prime the engine, the valve 26 is moved to 20 its intermediate position to cover the outlet ports, and the desired quantity of hydrocarbon is placed in cup 42. When the valve 25 43 is opened the hydrocarbon passes through pipe 41 into the outlet chamber 23, and from thence to the manifold. In the same manner kerosene may be introduced to the engine cylinder, without interrupting the operation of the engine, for the purpose of cleaning off carbon deposit.

From the foregoing it will be seen that 30 our improved auxiliary air device is simple in construction, and is capable of supplying air at the desired temperature, to conform to the requirements of the engine, thereby insuring economical and efficient operation 35 of the latter. It will also be noted that the device is readily controlled.

Having thus explained the nature of our invention and described an operative manner of constructing and using the same, 40 although without attempting to set forth all of the forms in which it may be made, or all of the forms of its use, what we claim is:—

1. A valve of the character described comprising a valve casing having independent, spaced-apart inlet passages and spaced-apart outlet passages, the outlet passages leading from the casing at a point between the inlet passages, and a slide valve 50 mounted to reciprocate longitudinally within said casing to selectively close all of said passages.

2. A valve of the character described comprising an elongated valve casing having independent, spaced-apart inlet passages and spaced-apart outlet passages, the inlet and outlet passages being arranged in alinement, a delivery pipe for connecting the outlet passages with the engine manifold, 60 and a slide valve mounted to reciprocate longitudinally within the casing to selectively close the inlet and outlet passages.

3. A valve of the character described comprising a valve casing provided with removable end caps, one of which is provided

with an opening, said casing being provided with spaced-apart inlet passages and spaced-apart outlet passages, the outlet passages leading from the casing at a point between the inlet passages, a slide valve mounted to reciprocate longitudinally within said casing to selectively control said inlet and outlet passages, and an operating rod attached to one end of said valve and extended through the opening in said end cap. 75

4. A valve of the character described comprising a valve casing having independent spaced-apart inlet passages and spaced-apart outlet passages, the outlet passages leading from the casing at a point between the air inlet passages, a slide valve mounted to reciprocate within said casing to selectively close all of said passages, and means for locking the valve in position to cover all of the outlet passages. 80 85

5. A valve of the character described comprising a casing having a valve chamber and an outlet chamber, passages being provided between said valve chamber and said outlet chamber, said valve chamber having inlet openings spaced from each other with the outlet openings between them, said casing being also provided with a supplemental passage extending transversely thereof and leading to the outlet chamber, and a slide valve mounted to reciprocate within the valve chamber to selectively control the inlet and outlet passages. 90

6. A valve of the character described comprising a casing having a valve chamber 100 provided with independent spaced apart inlet passages and spaced apart outlet passages, the latter being located between the inlet passages, a hollow cylindrical valve, closed at one end, and slidably mounted within said casing, and an operating rod attached to the closed end of said valve and extending through one end of said casing. 105

7. A valve of the character described comprising a valve casing having inlet and outlet passages, said outlet passages having a common discharge passage, a slide valve within said casing controlling said passages, said casing having a supplemental passage in alinement with said discharge passage, 110 and means for closing said supplemental passage. 115

8. A valve of the character described comprising a valve casing having inlet and outlet passages in its side wall, said outlet passages having a common discharge passage, a slide valve within said casing controlling said passages, said casing having a supplemental passage in alinement with said discharge passage, means for closing said supplemental passage, and a valve stem extended through one end of said casing and attached to said slide valve. 120 125

9. A valve of the character described comprising a valve casing having inlet and out- 130

let passages, and oppositely extended transverse bosses, said outlet passages communicating with one of said bosses, a slide valve within said casing controlling said outlet passages, and means for closing the other boss.

In testimony whereof we have hereunto

set our hands in presence of two subscribing witnesses.
